United States Patent Office

Des. 193,988
Patented Nov. 6, 1962

193,988

CAN OPENER

Ira W. Schwartz, Great Neck, N.Y., assignor to Landers,
Frary & Clark, New Britain, Conn., a corporation of
Connecticut

Filed June 9, 1961, Ser. No. 65,531

Term of patent 7 years

(Cl. D22—2)

FIG. 1

FIG. 2

FIG.3

FIG. 4

FIG. 5

FIG. 1 is a perspective view of a can opener embodying my new design;

FIG. 2 is a reduced scale perspective view thereof showing the can opener cover in open position;

FIG. 3 is a reduced scale front elevational view thereof;

FIG. 4 is a right end view of the can opener of FIG. 3; and

FIG. 5 is a bottom plan view of the can opener in FIG. 3.

The dominant features of my design reside in the portions shown in full lines.

I claim:

The ornamental design for a can opener, as shown and described.
